CLAIM

The ornamental design for a spout, as shown and described.

DESCRIPTION

FIG. 1 is a perspective view taken from the top front and right side showing the spout;

FIG. 2 is a front view of the spout;

FIG. 3 is a rear view of the spout, including an outline in broken form where features not forming part of the claimed design are omitted;

FIG. 4 is a right view of the spout;

FIG. 5 is a left view of the spout;

FIG. 6 is a bottom view of the spout; and,

FIG. 7 is a top plan view of the spout.
